UNITED STATES PATENT OFFICE.

GEORGE L. PIERCE AND RALPH B. NICKERSON, OF NEW YORK, N. Y., ASSIGNEES TO A. G. SPALDING & BROS., OF JERSEY CITY, NEW JERSEY, A CORPORATION OF NEW JERSEY.

LEG-GUARD FOR ATHLETES.

No. 909,215.

Specification of Letters Patent. Patented Jan. 12, 1909.

Application filed February 19, 1908, Serial No. 416,779. Renewed October 13, 1908. Serial No. 457,528.

To all whom it may concern:

Be it known that we, GEORGE L. PIERCE, residing in the borough of Brooklyn, of the city of New York, in the State of New York, and RALPH B. NICKERSON, residing in the borough of Manhattan, of the city of New York, in the State of New York, both citizens of the United States, have invented 5 certain new and useful Improvements in 10 Leg-Guards for Athletes, of which the following is a specification, reference being had to the accompanying drawing, forming a part hereof.

It is customary among hockey players and 15 cricket players and the like to wear for the protection of the lower leg what is commonly called a shin guard, the same usually comprising a substantially semi-circular 20 guard of relatively stiff or rigid material, suitably padded on the inner side and provided with straps and suitable fastening 25 devices for securing it to the leg below the knee. Sometimes such guard or protector is extended upwardly so as to protect the 30 knee to some extent, but such extension is integral with the lower portion of the guard or protector and therefore interferes to some extent with the free movement of the leg, besides failing to properly protect the knee when the knee is flexed.

It is the object of the present invention to 35 provide an improved leg guard which shall combine both a shin guard and a knee guard and shall properly and effectually protect both the shin and the knee without interfering 40 with the free movements of the leg in running, &c. In accordance with the invention the shin guard is formed substantially as heretofore of relatively stiff and rigid material and is connected at its upper end 45 by a flexible section, also suitably padded, with a knee guard of relatively stiff and rigid material suitably padded interiorly. Both the shin guard and the knee guard are provided with suitable means for securing them in position.

The invention will be more fully explained hereinafter with reference to the 50 accompanying drawing in which it is illustrated and in which—

Figure 1 is a view in elevation showing the improved leg guard in position, the leg

being indicated in part by dotted lines. Fig. 2 is a vertical central section of the guard. 55

As represented in the drawing the shin guard *a* may be formed of a sheet of fiber or other relatively stiff and rigid material, and may be provided with pads *b* and with straps *c* for securing it in position upon the 60 leg. The knee guard is similarly formed of a sheet *d* of fiber or other relatively stiff and rigid material, being suitably shaped to protect the knee cap and knee joint and padded 65 interiorly, as at *e*, and provided with a strap or other means *f* by which it may be secured in position. The two portions *a* and *d* of the improved guard are connected by a soft and flexible section *g*, preferably of soft leather, which is also padded interiorly, as at *h*. 70 The flexible section *g* is relatively short and the leg is therefore but little exposed to injury by blows between the stiff and rigid sections *a* and *d*, but it is nevertheless desirable, in order to guard against possibility 75 of injury, that the flexible section *g* be padded interiorly, so that any chance blow will be cushioned.

It will be seen not only that the improved leg guard affords the desired protection to 80 the shin and to the knee by the stiff and stout sections *a* and *d*, but that these two sections are united in one structure by the intermediate flexible section *g*, yet without interference with the free movements of the 85 leg in running, &c.

We claim as our invention:

1. A leg guard for athletes comprising 90 shin and knee sections of relatively stiff and rigid material, fastening means for securing the same in position upon the leg and an intermediate, relatively flexible section uniting the two stiff sections.

2. A leg guard for athletes comprising 95 shin and knee sections of relatively stiff and rigid material padded interiorly, and an intermediate, relatively flexible section uniting the two stiff sections and also padded interiorly.

This specification signed and witnessed 100 this 14th day of February, A. D., 1908.

GEORGE L. PIERCE.

RALPH B. NICKERSON.
